CLAIM

The ornamental design for the “vertical roaster,” as shown and described.

DESCRIPTION

FIG. 1 is a perspective view of the roaster.

FIG. 2 is a perspective view of the roaster taken from the bottom thereof.

FIG. 3 is a left side elevational view of the roaster.

FIG. 4 is a front elevational view of the roaster.

FIG. 5 is a right side elevational view of the roaster.

FIG. 6 is a rear elevational view of the roaster.

FIG. 7 is a top view of the roaster; and,

FIG. 8 is a bottom view of the roaster.
